UNITED STATES PATENT OFFICE.

ERNEST K. HOOD, DECEASED, BY HARRIET H. HOOD, ADMINISTRATRIX, OF INDIANAPOLIS, INDIANA, ASSIGNOR TO AMERICAN SLICING MACHINE COMPANY, OF CHICAGO, ILLINOIS, A CORPORATION OF NEW YORK.

SLICING MACHINE.

Original application filed July 2, 1919, Serial No. 308,218. Patent No. 1,372,023, dated March 22, 1921.
Divided and this application filed August 2, 1920. Serial No. 400,774.

To all whom it may concern:

Be it known that I, HARRIET H. HOOD, a citizen of the United States, and residing at Indianapolis, in the county of Marion and State of Indiana, administratrix of ERNEST K. Hood, deceased, late a citizen of the United States, am in possession of a certain new and useful Improvement in Slicing Machines, of which the following is a specification.

This invention relates to a slicing machine and particularly to a means for sharpening the rotary knife used in connection with the slicing machine. It is a division of my co-pending application bearing Serial Number 308,218, filed July 2, 1919.

It has been found in practice that bread is best cut by means of a knife having an involute curve for the cutting edge. Many machines of this type have been built but it has been found very difficult to sharpen such a knife. In my invention I provide means for automatically sharpening the knife.

My invention is illustrated more or less diagrammatically in the accompanying drawings wherein:

Figure 1 is a partial plan view of a slicing machine;

Figure 2 is an end elevation;

Figure 3 is a side elevation of the sharpening roller on an enlarged scale.

Like parts are designated by like characters throughout the drawings.

A is a base plate which carries the supporting frame A'. B is the bearing mounted in the supporting frame. B' is a feed screw carried by the bearing B. B² is a power shaft lying within the feed screw B' and adapted to rotate the knife C which is mounted upon it and has a curved cutting edge, preferably an involute curve. D D indicate parts of the bread carrying and supporting mechanism which form no part of this present invention and therefore, are not illustrated or explained in detail. E is a sharpening roller composed of emery or similar material. Its length is equal to the longest radius of the involute curve of the knife. The roller E is mounted in the frame E'. Its mounting may or may not include ball bearings. The frame E' is carried on a swinging arm E² which is pivoted at E³ to the bracket E⁴ rotated adjacent the knife.

The roller E is so positioned that one end of it will be contacted by that portion 55 of the knife blade which is closest to the hub of the knife. As the knife rotates, its blade will successively contact the surface of the roller at different points and the point of the knife will contact the other end of 60 the roller.

The spring F holds the swinging arm E² in the proper position so as to bear against the knife blade and the adjusting screw G determines the initial location of the arm. 65 A stud and nut F' holds the sharpener out of the path of the knife when it is desired to keep the sharpener out of the operative position. F² is a groove into which the nut F' may be dropped. F³ F³ are notches adjacent the groove F².

The use and operation of this invention are as follows:

This device may be used for cutting a large variety of materials but it is preferably used for cutting bread. In cutting bread, a knife blade is very rapidly dulled and it is therefore necessary to provide means for sharpening the blade at frequent intervals. For this purpose, the sharpening assembly above described is provided. Normally the sharpening roller is held against the blade of the knife by the spring and the knife blade is sharpened with every revolution. This arrangement may of course, be varied so as to make the sharpening less frequent. As the knife blade rotates, that point of the blade nearest the hub is the first to contact the face of the roller. As the rotation continues, the point of contact between 90 the roller and the knife blade shifts and during one complete revolution of the blade the roller is contacted throughout its entire length and the entire blade is sharpened. During this rotation as the blade travels 95 along the surface of the roller, the swinging arm which carried the roller mounting is forced back against the resistance of the spring. When the point of the blade has passed from the roller the spring forces the 100 roller forward again so as to bring it in contact with the other end of the blade as that revolves into position. During the sharpening, the roller rotates in response to the movement of the knife blade. The knife edge has a sliding advance action on the

emery roller and thus the blade is very rapidly sharpened.

When it is desired to throw the sharpening mechanism out of operation, the stud 5 and nut F' are withdrawn from the groove F² and the nut is turned through a quarter of a revolution and allowed to drop into the notches F³ F³ thus the sharpening mechanism is held out of operating contact with 10 the knife blade.

I claim:

In a slicing machine having a spiral edged knife adapted to rotate across the end there-

of, a sharpening device for the knife comprising a pivoted frame, a cylindrical, elongated grinding roller adapted to lie in the path of the edge of the knife and resilient means for rotating said frame into the path of said knife and holding said roller against said knife. 15

Signed at Cincinnati, county of Hamilton and State of Ohio, this 27 day of July, 1920. 20

MRS. HARRIET H. HOOD,
Administratrix for the estate of Ernest K.
Hood, inventor, deceased.
